US00D738915S

(12) **United States Design Patent** (10) **Patent No.:** **US D738,915 S**
Park (45) **Date of Patent:** **** Sep. 15, 2015**

(54) **DISPLAY SCREEN OR PORTION THEREOF
WITH ICON**

(71) Applicant: **Samsung Electronics Co., Ltd.**,
Suwon-si (KR)

(72) Inventor: **Eun-Hae Park**, Gimpo-Si (KR)

(73) Assignee: **Samsung Electronics Co., Ltd.**,
Suwon-si (KR)

(**) Term: **14 Years**

(21) Appl. No.: **29/457,401**

(22) Filed: **Jun. 10, 2013**

(30) **Foreign Application Priority Data**

Feb. 23, 2013 (KR) 30-2013-0009590

(51) **LOC (10) Cl.** **14-04**

(52) **U.S. Cl.**

USPC **D14/492**

(58) **Field of Classification Search**

USPC D14/485-489, 492, 494, 495; D20/11,
D20/12, 23, 27, 29

CPC G06F 3/04817; G06F 3/0482

(57) **CLAIM**

The ornamental design for a display screen or portion thereof with icon, as shown and described.

DESCRIPTION

FIG. 1 is a front view of a display screen or portion thereof with icon, showing my new design; and,

FIG. 2 is a front view of a second embodiment thereof. The broken lines showing the display screen are included for the purpose of illustrating environmental structure and form no part of the claimed design.

1 Claim, 2 Drawing Sheets

FIG. 1

FIG. 2
